CLAIM

The ornamental design for a baby sunglasses with strap, as shown and described.

DESCRIPTION

FIG. 1 is a front perspective view of a baby sunglasses with strap, showing my new design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of the area labeled 9 in FIG. 1 showing the strap detail.

The broken lines shown in the drawings are included for the purpose of illustrating portions of the baby sunglasses with strap that form no part of the claimed design.
